UNITED STATES PATENT OFFICE

153,931

DESIGN FOR AN AUTOMOBILE CARRYING TRAILER

Lynn M. Francis, Detroit, Mich.

Application March 10, 1947, Serial No. 137,485

Term of patent 7 years

(Cl. D14—3)

To all whom it may concern:

Be it known that I, Lynn M. Francis, a citizen of the United States, residing at Detroit, Wayne County, Michigan, have invented a new, original, and ornamental Design for an Automobile Carrying Trailer, of which the following is a specification, reference being had to the accompanying drawings, forming a part thereof, wherein:

Fig. 1 is a side perspective view taken essentially from the front, above, and one side of an automobile carrying trailer, embodying the design of the present invention;

Fig. 2 is essentially an enlarged side elevation of the trailer shown in Fig. 1, and showing its relation to a truck in phantom for illustrative purposes only; and

Figs. 3, 4 and 5 are essentially enlarged top, front and rear views, respectively, of the trailer shown in Fig. 1.

I claim:

The ornamental design for an automobile carrying trailer, as shown and described.

LYNN M. FRANCIS.
